UNITED STATES PATENT OFFICE.

HARRY H. HUNT, OF LOS ANGELES, CALIFORNIA.

DESIGN FOR A CASING FOR A VENDING MACHINE.

Application filed February 17, 1926. Serial No. 16,547. Term of patent 7 years.

To all whom it may concern:

Be it known that I, HARRY H. HUNT, a citizen of the United States, residing at Los Angeles, in the county of Los Angeles and State of California, have invented a new, original, and ornamental Design for Casing for a Vending Machine, of which the following is a specification, reference being had to the accompanying drawings, forming a part thereof.

In the accompanying drawing Fig. 1 is a perspective view of a casing for a vending machine showing my new design, and Fig. 2 is a top plan view of the casing.

I claim:

The ornamental design for a casing for a vending machine substantially as shown.

HARRY H. HUNT.
